CLAIM

The ornamental design for a siren, as shown and described.

DESCRIPTION

FIG. 1 is a perspective view of a siren for showing a new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a detail view thereof, wherein the siren has a bowed shape and the siren comprises a protuberant assembly on two sides of the siren to facilitate the emplacement and disassembly of the siren, an impeller-like vocal hole is located on a front end of the siren to enlarge the sound, a metal frame is fixed on a bottom of the siren to maintain the siren on a horizontal plane, and a screw is located on the bottom of the siren to adjust an angle of elevation of the siren.
